UNITED STATES PATENT OFFICE.

LOUIS L. DRIGGS, OF SHARON, PENNSYLVANIA, AND ERNEST WILKINSON,
OF WASHINGTON, DISTRICT OF COLUMBIA; SAID WILKINSON ASSIGNOR
TO SAID DRIGGS.

SHELL-FUSE.

No. 823,852.

Specification of Letters Patent.

Patented June 19, 1906.

Application filed October 13, 1905. Serial No. 282,632.

To all whom it may concern:

Be it known that we, LOUIS L. DRIGGS, residing at Sharon, in the county of Mercer and State of Pennsylvania, and ERNEST WILKINSON, residing at Washington, in the District of Columbia, citizens of the United States, have invented certain new and useful Improvements in Shell-Fuses; and we do hereby declare the following to be a full, clear, and exact description of the invention, such as will enable others skilled in the art to which it appertains to make and use the same.

Our invention relates to improvements in shell-fuses; and it is more especially intended for use with heavy shell, which are more cumbersome and dangerous to handle than the smaller shell and which if prematurely exploded are apt to cause vastly more damage than the smaller shell. It is intended also in certain types of shell to do away with the bouching for the fuse-stock, which is generally screwed into the body of the shell and which weakens the shell by increasing the size of the fuse-opening therein. It is further intended to provide against accident in emptying loaded shells and refilling same, which accidents are presumably most frequently caused by the grinding of fine particles of powder-dust in the screw-threads of the fuse-stock, which powder-dust has sifted into the lost space between said screw-threads.

Our invention is further intended to provide a shell-fuse in which the explosive material is normally kept out of the fuse while the shell is being shipped from place to place either afloat or ashore or from the magazines to the battery aboard ship, but in which the parts carrying the explosive may be readily inserted just before the shell is delivered at the gun.

According to our invention the parts of the fuse carrying the primer may be stowed at any convenient point outside of the magazines and may be safely carried in the pockets of those serving the gun and inserted in the fuse when desired, but which when inserted in the fuse are still safe under all standard conditions incident to handling of the shell except when the shell is set spinning, due to the rifling in the gun.

While our invention is especially intended for use with large shell, it is none the less efficient if used with small shell.

Our invention will be understood by the accompanying drawings, in which four embodiments thereof are shown, two being for a base-fuse and the other two being for a point-fuse.

Figure 1 shows a section through the base of the shell and the center of the fuse-stock with the plunger and centrifugal arms for holding the same shown in elevation, the parts being assembled. Fig. 2 shows a section through the fuse-stock and cap at right angles to the section of Fig. 1 and shows the plunger and connected parts as seen from the left of Fig. 1, the three parts being shown in the position ready for assembling. Fig. 3 shows an axial section through the nose of a shell with all the parts of the fuse shown in section. Fig. 4 shows a section through the nose of the shell and the cap at right angles to the section of Fig. 3, with a side view of the plunger and connected parts as seen from the left of Fig. 3. In Fig. 4 the three parts are shown in position ready for assembling and the parts are broken away. Fig. 5 shows a modification in which the fuse-stock is provided with a shoulder to hold the plunger in place, and Fig. 6 shows a plunger for use in the stock shown in Fig. 5. Figs. 5 and 6 are on a much smaller scale than are the other figures. Fig. 7 shows the plunger inclosed in a small bag, of kid or other soft material, provided with a perforated end, parts being broken away. Fig. 8 shows a plunger inclosed in a similar bag with oiled paper pasted over the opening in said bag. Fig. 9 shows a point-fuse in which the fuse-stock is integral with the shell, and Fig. 10 shows a base-fuse in which the fuse-stock is integral with the shell.

Referring first to Figs. 1 and 2, A represents the base of the shell, screw-threaded, as at *a*, to receive the screw-threads *b* of the fuse-stock *B*. Across the bottom of this fuse-stock is secured a stout pin *C*, which pin is adapted to engage in a notch *d* in the bottom of the anvil *D*, which carries the percussion-primer *E* in front of the hole *d*. This pin *C* serves to prevent the anvil from dropping into the shell and also causes the said anvil to rotate with the fuse-stock, and thereby with the shell. Secured to said anvil in any convenient way, as by means of the pins *f*, is a spring-piece *F*, recessed, as at *f*, (see dotted lines in Fig. 1,) to permit the firing-pin *h* to

strike the primer E when the plunger H is released. This spring-piece F has arms F' terminating in weights F². The arms F' normally project into notches h⁰ in the plunger H, and the weights F² are curved inwardly and engage in the annular groove H² beneath the collar H' of the plunger. When the shell is spinning, these weights are thrown outward to clear the collar H' and the plunger 5 is free to fly forward on impact with the target, as described in the patent to William H. Driggs, No. 419,143, dated January 7, 1890. The fuse-stock B projects somewhat in rear of the shell, as shown in Figs. 1 and 2, and is 10 normally closed by means of a cap K and a washer, of leather or other like material, I. This cap is interiorly screw-threaded, as at k, and is provided with a boss k', adapted to engage the back of the plunger H when the 15 parts of the fuse are assembled, as shown in Fig. 1. This cap K is provided with suitable notches k² to engage a wrench or spanner, so that said cap may be readily removed when desired. A disk of oiled paper G is preferably 20 pasted or cemented over the bottom of the anvil, as shown in Figs. 1 and 2, which paper will be ruptured beneath the notch d when the fuse is assembled.

The form of device shown in Figs. 3 and 4 is 25 generally similar to that shown in Figs. 1 and 2, except that the nose of the shell A' is screw-threaded, as at a, to receive the screw-threads b of the fuse-stock B. The pin C is made stouter, since it will have to stand the shearing effect 30 of the plunger and the parts carried thereby when the gun is fired. Moreover, the cap K forms the nose of the shell and is notched, as at k², to receive a suitable wrench or spanner. Furthermore, the boss k' is provided with 35 the firing-pin k⁰ to engage the primer E' when the weights F² swing outward under centrifugal force. In this form of device the plunger M carries the nipple m³, on which is mounted the primer E', and the spring-piece 40 F is secured to and moves with the plunger, it being inserted in a notch m across the base of the plunger and held in place in any convenient way, as by pins f². The arms F' of this spring-piece engage in notches m' in the 45 side of the plunger, and the weights F², which are curved inwardly, project in front of the said plunger and form a positive stop between it and the face of the abutment k', except when the shell is spinning. When the 50 shell is spinning, these weights fly outward under the action of centrifugal force, and the slowing down of the shell, due to the resistance of the air, causes the said weights to creep up into the annular grooves surrounding 55 this boss k', and therefore keep the fuse primed or in the firing position after the gun has been fired and even after the shell has slowed down so much that the centrifugal force would no longer cause the weights F² to 60 swing outward against the action of the 65

spring-arms F'. A disk of oiled paper or tin-foil may be pasted over the bottom of the plunger, as already described with reference to Figs. 1 and 2, or an annular disk of leather or kid or the like may be pasted or cemented 70 over the bottom of the plunger, as shown at G'.

In the form of device shown in Figs. 5 and 6 a tapered shoulder b⁴ is provided on the lower end of the fuse-stock B' and a lug b⁵ is 75 provided to project into the slot m of the plunger M', and thus to keep said plunger from turning. This plunger M' is provided with a tapered end m⁴ to engage the shoulder b⁴, and thus prevents the plunger from dropping 80 into the shell when the gun is fired.

In the device shown in Figs. 7 and 8 the plunger is inclosed in a bag, of kid or other similar soft material, P, preferably provided with a small hole p in its tip for the passage 85 of the flame from the primer, while in Fig. 8 this hole is shown somewhat larger, as at p', and closed with a patch of oiled paper p². A draw-string p⁰ may be used in the top of the bag. This bag will not only protect the plunger while being manipulated, but will also limit the sifting of any powder grains upward and will prevent the plunger from sticking 90 in the fuse and will afford a convenient means for pulling it out when desired. It 95 will be seen that this bag will not in any way interfere with the operation of the fuse. It will be evident from inspecting the drawings that the fuse-stock may be permanently kept in the shell and the opening through the 100 stock normally closed by a suitable cap, while the washer I, of leather or like soft material, prevents the sifting of any powder grains to the screw-threads of the cap. It will be evident that the shell may be loaded and unloaded 105 through the opening in the fuse-stock with perfect safety if proper precautions are taken in loading and unloading.

In the form of device shown in Fig. 9 the fuse-stock is cast integral with the shell A², the ordinary hole being left in the nose of the shell and this being bored out to leave a shoulder a³ at its base. To lengthen the hole for the fuse, if desirable, the inner projection a² 110 may be cast in the shell. The nose of the 115 body of the shell is cut away, as at a', and screw-threaded, as at a, to engage the cap K. The shoulder a³ may be slotted, as at a⁰, to receive the spline-pin m⁰, fast to the plunger M, which prevents said plunger from rotating 120 in the shell. The construction of the parts is otherwise substantially the same as has already been described with reference to Figs. 3 and 4.

In the form of device shown in Fig. 10, A³ 125 represents the base of a cast shell, which is provided with the screw-threaded projection a' for the cap K and with the inner projection a⁴, having a tapered shoulder a⁵ to engage the conical face d⁵ of the plunger D. This 130

shoulder a^5 may be slotted, as at a^6 , to receive the spline-pin m^6 , fast to the anvil D. The construction and operation of the parts is otherwise precisely similar to that already described with reference to Figs. 1 and 2.

The firing mechanism of the fuse shown in Figs. 9 and 10 may be removed therefrom at a single operation, and when the shell is being transported it would be preferable to have the firing mechanism removed and a cork or other stopper inserted in the fuse-hole and the cap screwed on. The cork or stopper should of course be removed before inserting the firing mechanism. It will be evident that this firing mechanism shown in Figs. 9 and 10 might be normally contained in a bag similar to that shown in Figs. 7 and 8 and either inserted in the shell while still contained in said bag or might be removed from the bag before insertion, as desired.

It will be evident that in all the forms of fuse herein described the primer and active parts of the fuse may be carried entirely separate from the shell and the danger due from accidental explosions of the shell in transit may be largely avoided. By having these active parts of the fuse normally entirely separate from the shell and inserted only just before firing it is always possible to conveniently inspect these parts and see whether the fuse is thoroughly in order. This is very important, as the failure of the fuse to operate may, as it has done in the past, be productive of most serious results. Furthermore, by doing away with the bouching for the fuse-stock, and thus reducing the necessary diameter of the opening in the shell, not only may greater strength of the shell be secured, but also, other things being equal, a larger plunger may be provided, and consequently a greater blow on the primer may be secured, so that the fuse will operate even after the shell is almost spent.

It will be seen that the plunger and primer and other parts may be removed or inserted by a straight motion without any turning whatever, so that there is no tendency to grind powder grains and no likelihood of premature ignition from any cause, and this safety is further increased by putting the plunger and parts carried thereby in a bag, of kid or like material, as illustrated in Figs. 7 and 8.

It will be obvious that various modifications might be made in the herein-described apparatus which could be used without departing from the spirit of our invention.

Having thus described our invention, what we claim, and desire to secure by Letters Patent of the United States, is—

1. A shell-fuse for large-caliber projectiles comprising three separate parts adapted to be readily assembled and disassembled, to wit, a fuse-stock permanently attached to the shell and having a bore adapted to permit the ready introduction and removal of the burst-

ing charge, a cap adapted to be secured on said fuse-stock, and percussion firing mechanism mounted in the bore of said fuse-stock beneath said cap and capable of being independently inserted in or removed from said stock at one operation, substantially as described.

2. A shell-fuse comprising three separate parts adapted to be readily assembled and disassembled, to wit, a fuse-stock, a cap adapted to be secured on said fuse-stock, and firing mechanism mounted in said fuse-stock beneath said cap and capable of being inserted in or removed from said stock at one operation, with a bag of kid or other soft material inclosing said firing mechanism, substantially as described.

3. A shell-fuse for large-caliber projectiles comprising three separate parts adapted to be readily assembled and disassembled, to wit, a fuse-stock provided with external screw-threads adapted to engage in the shell and to project therefrom, the said fuse-stock being permanently attached to the shell, and having a bore adapted to permit the ready introduction and removal of the powder charge, a cap adapted to be screwed on said fuse-stock, on the projecting portion thereof, and percussion firing mechanism mounted in the bore of said fuse-stock beneath said cap and capable of being inserted in or removed from said stock at one operation, substantially as described.

4. A shell-fuse comprising three separate parts adapted to be readily assembled and disassembled, to wit, a fuse-stock, provided with external screw-threads adapted to engage in the shell and to project therefrom, a cap adapted to be screwed on said fuse-stock, on the projecting portion thereof, and firing mechanism mounted in said fuse-stock beneath said cap and capable of being inserted in or removed from said stock at one operation, with a bag of kid or other soft material engaging said firing mechanism, substantially as described.

5. A shell-fuse for large-caliber projectiles comprising three separate parts adapted to be readily assembled and disassembled, to wit, a fuse-stock provided with external screw-threads adapted to engage in the shell and to project therefrom, the said fuse-stock being permanently attached to the shell, and having a bore adapted to permit the ready introduction and removal of the powder charge, a cap adapted to be screwed on said fuse-stock, on the projecting portion thereof, an annular washer of leather or similar material held in said cap and adapted to form a tight joint with the end of said fuse-stock, and firing mechanism mounted in said fuse-stock beneath said cap and capable of being inserted in or removed from said stock at one operation, substantially as described.

6. A shell-fuse for large-caliber projectiles

- comprising three separate parts adapted to be readily assembled and disassembled, to wit, a fuse-stock permanently attached to the shell and having a bore adapted to permit the ready introduction and removal of the bursting charge, a cap adapted to be secured on said fuse-stock, and percussion firing mechanism mounted in the bore of said fuse-stock beneath said cap and capable of being independently inserted in or removed from said stock at one operation, with means carried by or integral with said stock for holding said firing mechanism in said stock beneath said cap, substantially as described.
15. A shell-fuse comprising three separate parts adapted to be readily assembled and disassembled, to wit, a fuse-stock having a pin across its inner end, a cap adapted to be secured on said fuse-stock, and firing mechanism mounted in said fuse-stock beneath said cap and engaging said pin, substantially as described.
20. A shell-fuse comprising three separate parts adapted to be readily assembled and disassembled, to wit, a fuse-stock adapted to be secured in the shell and having a pin across its inner end, a cap adapted to be secured on said fuse-stock, and firing mechanism mounted in said fuse-stock beneath said cap and provided with a transverse groove to engage said pin, substantially as described.
25. A shell-fuse comprising three separate parts adapted to be readily assembled and disassembled, to wit, a fuse-stock adapted to be secured in the shell and having a pin across its inner end, a cap adapted to be secured on said fuse-stock, and firing mechanism mounted in said fuse-stock beneath said cap and provided with a transverse groove to engage said pin, with a bag of kid or other soft material inclosing said firing mechanism, substantially as described.
30. A shell-fuse comprising three separate parts adapted to be readily assembled and disassembled, to wit, a fuse-stock, a cap adapted to be secured on said fuse-stock, and firing mechanism adapted to be put in operative position by the spinning of the shell mounted in said fuse-stock beneath said cap and capable of being inserted in or removed from said stock at one operation, with means for holding said firing mechanism against rotation relative to said stock, and a bag of kid or other soft material inclosing said firing mechanism, substantially as described.
35. A shell-fuse comprising three separate parts adapted to be readily assembled and disassembled, to wit, a fuse-stock provided with external screw-threads adapted to engage in the shell and to project therefrom, a pin extending across the inner end of said fuse-stock, a cap adapted to be screwed on said fuse-stock, on the projecting portion thereof, and firing mechanism provided with a notch engaging said pin, mounted in the bore of said stock beneath said cap and capable of being inserted in or removed from said stock at one operation, substantially as described.
40. A shell-fuse comprising three separate parts adapted to be readily assembled and disassembled, to wit, a fuse-stock provided with external screw-threads adapted to engage in the shell and to project therefrom, a pin extending across the inner end of said fuse-stock, a cap adapted to be screwed on said fuse-stock, on the projecting portion thereof, and firing mechanism provided with a notch engaging said pin, mounted in the bore of said stock beneath said cap and capable of being inserted in or removed from said stock at one operation, with a bag of kid or other soft material engaging said firing mechanism, substantially as described.
45. A shell-fuse comprising three separate parts adapted to be readily assembled and disassembled, to wit, a fuse-stock, a cap adapted to be secured on said fuse-stock, and firing mechanism adapted to be put in operative position by the spinning of the shell mounted in said fuse-stock beneath said cap and capable of being inserted in or removed from said stock at one operation, with means for holding said firing mechanism against rotation relative to said stock, and a bag of kid or other soft material inclosing said firing mechanism, substantially as described.
50. A shell-fuse comprising three separate parts adapted to be readily assembled and disassembled, to wit, a fuse-stock provided with external screw-threads adapted to engage in the shell and to project therefrom, a pin extending across the inner end of said fuse-stock, a cap adapted to be screwed on said fuse-stock, on the projecting portion thereof, and firing mechanism provided with a notch engaging said pin, mounted in the bore of said stock beneath said cap and capable of being inserted in or removed from said stock at one operation, substantially as described.
55. A shell-fuse comprising three separate parts adapted to be readily assembled and disassembled, to wit, a fuse-stock provided with external screw-threads adapted to engage in the shell and to project therefrom, a pin extending across the inner end of said fuse-stock, a cap adapted to be screwed on said fuse-stock, on the projecting portion thereof, and firing mechanism provided with a notch engaging said pin, mounted in the bore of said stock beneath said cap and capable of being inserted in or removed from said stock at one operation, substantially as described.
60. A shell-fuse comprising three separate parts adapted to be readily assembled and disassembled, to wit, a fuse-stock provided with external screw-threads adapted to engage in the shell and to project therefrom, a pin extending across the inner end of said fuse-stock, a cap adapted to be screwed on said fuse-stock, on the projecting portion thereof, and firing mechanism provided with a notch engaging said pin, mounted in the bore of said stock beneath said cap and capable of being inserted in or removed from said stock at one operation, substantially as described.
65. A shell-fuse comprising three separate parts adapted to be readily assembled and disassembled, to wit, a fuse-stock provided with external screw-threads adapted to engage in the shell and to project therefrom, a pin extending across the inner end of said fuse-stock, a cap adapted to be screwed on said fuse-stock, on the projecting portion thereof, and firing mechanism provided with a notch engaging said pin, mounted in the bore of said stock beneath said cap and capable of being inserted in or removed from said stock at one operation, substantially as described.

fuse-stock beneath said cap and capable of being inserted in or removed from said stock at one operation, substantially as described.

12. A shell-fuse comprising three separate parts adapted to be readily assembled and disassembled, to wit, a fuse-stock provided with external screw-threads adapted to engage in the shell and to project therefrom, a pin extending across the inner end of said fuse-stock, a cap adapted to be screwed on said fuse-stock, on the projecting portion thereof, and firing mechanism adapted to be put in the operative relation by the spinning up of the shell provided with a notch engaging said pin mounted in said fuse-stock beneath said cap and capable of being inserted in or removed from said stock at one operation, substantially as described.

13. A shell-fuse comprising three separate parts adapted to be readily assembled and disassembled, to wit, a fuse-stock provided with external screw-threads adapted to engage in the shell and to project therefrom, a pin extending across the inner end of said fuse-stock, a cap adapted to be screwed on said fuse-stock, on the projecting portion thereof, and firing mechanism adapted to be put in the operative relation by the spinning up of the shell provided with a notch engaging said pin mounted in said fuse-stock beneath said cap and capable of being inserted in or removed from said stock at one operation, substantially as described.

14. A shell-fuse comprising three separate parts adapted to be readily assembled and disassembled, to wit, a fuse-stock provided with external screw-threads adapted to engage in the shell and to project therefrom, a pin extending across the inner end of said fuse-stock, a cap adapted to be screwed on said fuse-stock, on the projecting portion thereof, and firing mechanism adapted to be put in the operative relation by the spinning up of the shell provided with a notch engaging said pin mounted in said fuse-stock beneath said cap and capable of being inserted in or removed from said stock at one operation, with a bag of kid or other soft material engaging said firing mechanism, substantially as described.

15. A shell-fuse for large-caliber projectiles comprising a substantially cylindrical fuse-stock having its bore open at both ends, a cap adapted to screw on the exterior of said stock, and percussion firing mechanism comprising the primer and means for exploding same, removably mounted in the bore of said stock beneath said cap, substantially as described.

16. A shell-fuse for large-caliber projectiles comprising a substantially cylindrical fuse-stock, having its bore open at both ends and exteriorly screw-threaded to screw into the shell, and adapted to project beyond the face of the shell, a screw-cap adapted to

screw over the projecting end of the fuse-stock, and a percussion primer and mechanism for exploding same, removably mounted in the bore of said stock beneath said cap, substantially as described.

5 17. A shell-fuse for large-caliber projectiles comprising a substantially cylindrical fuse-stock open at both ends, a cap adapted to screw on the exterior of said stock, a plunger mounted in said stock, a primer connected to and operated by said plunger, the said primer and plunger being removable at one operation from said stock, with means automatically operated by the spinning of the shell for causing said primer and plunger to assume the operative position relative to each other, substantially as described.

18. In a large-caliber shell, the combination with the shell-body, of a fuse-stock having its bore open at both ends and secured to or integral with the shell-body the said fuse-stock being adapted to permit the ready introduction and withdrawal of the bursting charge of the shell, percussion firing mechanism adapted to be held in the bore of said fuse-stock, and capable of being inserted in or removed from said stock at one operation, and a cap secured over the outer end of said fuse-stock, substantially as described.

25 19. In a large-caliber shell, the combination with the shell-body, of a fuse-stock having its bore open at both ends and secured to or integral with the shell-body the said fuse-stock being adapted to permit the ready introduction and withdrawal of the bursting charge of the shell, percussion firing mechanism adapted to be held in the bore of said fuse-stock, and capable of being inserted in or removed from said stock at one operation, 40 and a cap secured over the outer end of said fuse-stock, with a washer beneath said cap, substantially as described.

20. In a large-caliber shell, the combination with the shell-body, of a fuse-stock having its bore open at both ends and secured to or integral with the shell-body the said fuse-stock being adapted to permit the ready introduction and withdrawal of the bursting charge of the shell, percussion firing mechanism put in operative position by the spinning

up of the shell adapted to be held against turning in the bore of said fuse-stock, and capable of being inserted in or removed from said stock at one operation, and a cap secured over the outer end of said fuse-stock, substantially as described.

21. In a shell, the combination with the shell-body, of a fuse-stock open at both ends and secured to or integral with the shell-body, and provided with an outwardly-projecting portion exteriorly screw-threaded, firing mechanism put in operative position by the spinning up of the shell adapted to be held against turning in said fuse-stock, and capable of being inserted in or removed from said stock at one operation, and a cap screwed on over the projecting end of said fuse-stock, substantially as described.

22. In a point-fuse shell, the combination with the shell-body, of a fuse-stock open at both ends and secured to or integral with the shell-body and projecting forwardly therefrom, firing mechanism put in operative position by the spinning up of the shell adapted to be held against turning in said fuse-stock, and capable of being inserted in or removed from said stock at one operation, and a cap forming the nose of the shell secured over the outer end of said fuse-stock, substantially as described.

23. A shell-fuse comprising a substantially cylindrical fuse-stock, open at both ends and exteriorly screw-threaded to screw into the shell, and adapted to project beyond the face of the shell, a screw-cap adapted to screw over the projecting end of the fuse-stock, and a primer and mechanism for exploding same put into operative relation by the spinning up of the shell, removably mounted in said stock beneath said cap, with means for holding said mechanism in said stock and against turning therein, substantially as described.

In testimony whereof we affix our signatures in presence of two witnesses.
